UNITED STATES PATENT OFFICE.

DONALD P. ORDWAY, OF BATTLE CREEK, MICHIGAN, ASSIGNOR TO AMERICAN STAMP-
ING CO., OF BATTLE CREEK, MICHIGAN, A CORPORATION OF MICHIGAN.

GREASE CUP.

Application filed March 29, 1922. Serial No. 547,660.

To all whom it may concern:

Be it known that I, DONALD P. ORDWAY, a citizen of the United States, residing at Battle Creek, in the county of Calhoun and 5 State of Michigan, have invented certain new and useful Improvements in Grease Cups; and I hereby declare that the following is a full, clear, and exact description thereof, reference being had to the accompanying drawings, which form part of this 10 specification.

This invention is an improvement in grease cups and its object is to provide a grease cup with novel simple and effective means 15 to prevent the cover working off when the cup is used on vehicles or moving objects where it is subjected to jar or vibration.

This invention consists in the novel construction of cup cover and locking members 20 as hereinafter described and claimed; and the accompanying drawings illustrate practical embodiments of the invention which will be described with reference thereto.

In the said drawings:

25 Fig. 1 is a sectional view of a grease cup with my improved cover locking device.

Fig. 2 is a section on the line 2—2 Fig. 1.

Fig. 3 is a top plan view of the cup detached.

30 Fig. 4 is a section of the cover similar to Fig. 1, showing a simpler form of the spring locking member.

Fig. 5 is an inverted view of the cover detached.

35 The cup 1 may be of any desired form and construction, being shown as made of drawn metal and having a reduced tubular polygonal portion 1^a, and a lower threaded stem 1^b; the cup portion is exteriorly threaded 40 for engagement with the internal threads of the cup or cover 2, which may be of any suitable construction, and is also shown as made of drawn metal.

In carrying out my invention I provide 45 in or near the upper edge of the cup 1 a plurality of retaining members or protuberances preferably formed in the upper inner margin of the cup 1 by pressing the metal to form recesses as indicated at 3 in the drawings, such depression of the metal causes it to flare or project inwardly also as shown at 3^a, the inwardly projecting portions 3^a form locking members or protuberances around and within the upper edge 50 55 of cup 1 for engagement with a locking

member on the cover, and thereby prevent the cover from casually working off or unscrewing when the cup is subjected to jarring or vibration.

I preferably provide the base 1 with a 60 plurality of radially disposed retaining members such as depressions or protuberances on its inner conical surface as shown at 1^c, in Figs. 1 to 3, which will be engaged by the locking member on the cover 65 when the cover is screwed far down on the cup, and will prevent casual unscrewing of the cup.

As shown in Fig. 3 the recesses formed by 70 pressing the metal to form the locking members or protuberances do not affect the exterior of the cup, and leave sufficient metal for the continuity of the threads thereon and do not lessen the capacity of the cup. When these recesses are pressed in the upper 75 inner margin of the cup the adjacent metal flares out into the cup, the point of maximum width being adjacent the lowest portion of the recess, and such projecting portions form, as shown in Fig. 3, simple and 80 efficient retaining members or protuberances 85 3^a above referred to.

As stated these protuberances 3^a are adapted to be engaged with a locking member 85 on the cover 2. Preferably such locking member is formed of a flat strip 4 of spring metal the upper end of which is securely fastened to the underside of the top of the cover 2, and the strip is bent downward adjacent the inner side of the cover 2, 90 and extends to or slightly below the lower open end of the cover. The lower free end of the locking members is preferably cupped or rounded as at 4^a to facilitate the operative engagement of the cover 2 95 with the cup 1. The free end of the locking member may be straight, as in Fig. 4; or it may be provided with a bend 4^c above the rounded part 4^a, as shown in Fig. 1.

In the construction shown, the cover 2 100 can be very readily engaged with the cap 1, but when the threads are fairly engaged the free end of the locking member 4 will come into operative engagement with the locking members or protuberances 3^a and 105 prevent casual disengagement or backing off of the cover from the cup, although it will not prevent the cover being forcibly unscrewed by hand.

If the cover is screwed so far down that 110

the locking members do not effectively engage the radial protuberances 3^a they will then have engaged the radial protuberances 1^c and thus when the cover is screwed either 5 partly or fully down it will be prevented from casual working off or unscrewing when subjected to jarring or vibration, although it may be unscrewed by hand.

The retaining spring 4 is preferably attached to the cover as indicated in the drawings. For this purpose the cover 2 is 10 formed with an interior preferably elongated lug 2^a on its top, which is preferably formed integral with the cover by pressing 15 the metal of the cover top so as to form an exterior depression 2^b and an interior protuberance 2^a as shown in Figs. 1 to 3.

The upper part of locking member 4 extends diametrically or radially across the 20 underside of the top of cover 2 and has an opening or slot therein corresponding in shape to the lug 2^a, and when the slots in the member is engaged with the lug 2^a the metal of the lug is swaged over the 25 edge of the slot to securely fasten the locking member 4 to the cover 2; thus forming an efficient, economical, and oil tight rivet joint between the cap and locking member and obviating any possibility of oil leaking 30 through the riveted joint.

The invention enables the cover to be readily engaged with the cup when both are filled with grease; it preserves the full capacity of the cup for holding grease; it 35 cheapens the cost of connecting the cover and locking members; it facilitates the assembling of the parts; and it effectively prevents the cover from being casually unscrewed from the cup by jarring or shaking of the cup and cover when the cup is 40 applied to an automobile or other moving part.

I claim:

1. A grease cup exteriorly threaded and 45 having integral inwardly projecting retaining protuberances formed by depressing portions of the metal of the cup at its upper edge and inner side thereby producing inwardly projecting protuberances at

the bottom of the depression, substantially as and for the purpose specified.

2. A grease cup having interior integral protuberances adjacent its inner upper edge formed by depressing portions of the metal of the cup at its upper edge and inner side thereby producing inwardly projecting protuberances at the bottom of the depression; a cover; and a locking member in the cover having a depending portion adapted to engage the protuberances to prevent casual unscrewing of the cover.

3. A grease cup having integral protuberances adjacent its inner upper edge; a cover; and a locking member in the cover having a depending portion adapted to engage the protuberances to prevent casual unscrewing of the cover; said base also having radially disposed portions below the protuberances adapted to be engaged by the locking member when the cover is sufficiently screwed onto the cup.

4. A grease cup having recesses pressed in its inner side near its top thereby forming retaining protuberances adjacent its inner edge; a cover; and a locking member attached to the cover and having a depending portion adapted to engage the protuberances and prevent casual unscrewing of the cup; said base also having radially disposed portions below the protuberances adapted to be engaged by the locking member when the cover is sufficiently screwed onto the cup.

5. A hollow grease cup having integral retaining protuberances formed by pressing recesses in its top and inner side; a cover; and a locking spring in the cover and rigidly attached thereto, said spring having a depending portion adapted to engage the protuberances and prevent casual unscrewing of the cup; said base also having radially disposed portions below the protuberances adapted to be engaged by the locking member when the cover is sufficiently screwed onto the cup.

In testimony that I claim the foregoing as my own, I affix my signature.

DONALD P. ORDWAY.
